UNITED STATES PATENT OFFICE.

WILLIAM H. O'BRIEN, OF DENVER, COLORADO.

BELT.

Application filed August 17, 1923. Serial No. 657,963.

To all whom it may concern:

Be it known that I, WILLIAM H. O'BRIEN, a citizen of the United States of America, residing at Denver, in the county of Denver and State of Colorado, have invented 5 certain new and useful Improvements in Belts, of which the following is a specification.

This invention relates to belts as an 10 article of personal wearing apparel, and has for its principal object the provision of a belt having, as an integral part thereof, means for attaching the free extremity of a watch chain.

15 A further object of the invention is to so construct the watch chain attachment means, that it will in no way interfere with the comfort, use or efficiency of the belt should it be desired to make use of the belt 20 without making use of the attachment.

Other objects and advantages reside in the detail construction of the invention, which result in simplicity, economy and efficiency, and which will become more apparent from the following description.

In the following detailed description of the invention reference is had to the accompanying drawing which forms a part hereof. Like numerals refer to like parts 30 in all views of the drawing and throughout the description.

In the drawing:

Fig. 1 is an illustration showing the improved belt in use.

35 Fig. 2 is a detail view of the belt showing the watch chain attachment means.

Fig. 3 is a longitudinal section through a belt, at the watch chain attachment, showing the method of applying the attachment 40 to belts of the laminated type formed of two or more layers of material.

Fig. 4 is a similar view showing a method of securing the attachment to belts of the type formed of a single strip of material.

45 Fig. 5 is a view looking at the inside of a belt of the type illustrated in Fig. 4.

Fig. 6 is a detail view of the watch chain attachment before it is secured to the belt.

50 The belt, designated by the numeral 10, may be any of the usual types and constructions.

The watch chain attachment consists of a strip 12 of flexible material such as soft leather, formed preferably in the shape 55 shown in Fig. 6, comprising a relatively

narrow portion 13 terminating in relatively broad extremities 14.

In securing the attachment to those belts made of a single strip of leather or similar material an opening 11 is formed by punching completely through the belt. The narrow portion 13 of the attachment 12 is forced through this opening 11 and extends beyond the face of the belt as a flexible loop in which the free end of the watch chain, shown at 15, is held by the usual bar, 16, or button shaped guard with which the free extremities of watch chains are provided.

70 The broad extremities 14 of the attachment 12 are extended, substantially along the axis of the belt, in opposite directions, as shown in Figs. 4 and 5, and are sewed, cemented, riveted or otherwise secured to 75 the inner face of the belt to hold the attachment in place.

In the laminated type of belts which comprise two or more plies or layers of material, the opening 11 is formed only in the 80 outer ply, 17, as shown in Fig. 3, and the extremities 14 are secured between the outer ply 17 and the next inner ply 18, as indicated in the same view, no part of the attachment showing from the inner face of 85 the belt.

It is the custom to have the trouser watch pocket placed to the right of the trouser fly, and it is preferred to place the attachment 90 12 to the left of the belt buckle a distance 90 equal to the distance of the watch pocket from the trouser flap so that the watch chain will extend centrally across the trouser front, as illustrated in Fig. 1. Although this is the preferred location of 95 the device, it will be understood that it may be placed in any desired position.

The attachment, being of soft flexible material, will not interfere with the comfort or use of the belt with or without the use 100 of the attachment.

The size of the loop may be varied as desired but it is preferred to have it relatively large, as indicated in Fig. 2, to facilitate the insertion of the chain guard 105 therein.

While a specific form of the improvement has been described and illustrated herein it is desired to be understood that the same may be varied, within the scope of 110 the appended claims, without departing from the spirit of the invention.

Having thus described the invention, what is claimed and desired secured by Letters Patent is:—

1. The combination of a belt and an attachment for securing the free end of a watch chain to said belt, said attachment comprising a strip of flexible material passed through an opening in the face of said belt adjacent the buckle thereof, said strip forming a loop on the outside face of said belt and having its extremities extended in opposite directions and secured to the inside face of said belt.

2. Means for securing the free end of a watch chain to a detachable, buckle-secured, trouser belt comprising a loop of flat flexible material extending through an opening in said belt, the extremities of said loop extending in opposite directions along the axis of said belt and secured to the inner face thereof, said loop arranged to detachably engage the guard of a watch chain.

In testimony whereof, I affix my signature.

WILLIAM H. O'BRIEN.
